UNITED STATES PATENT OFFICE.

MARCUS C. STEARNS, OF CHICAGO, ILLINOIS.

IRONING BOARD.

Application filed October 24, 1921. Serial No. 510,027.

To all whom it may concern:

Be it known that I, MARCUS C. STEARNS, a citizen of the United States, residing at 5437 University Avenue, Chicago, in the county of Cook and State of Illinois, have invented a new and useful Improvement in Ironing Boards, of which the following is a specification.

This invention relates to improvements in 10 ironing boards, and more especially to an ironing board adapted to be detachably secured to a wall, and so constructed that it can be folded up against the wall when not in use. Other features of the invention and 15 advantages thereof will appear more fully as I proceed with my specification.

A form of device embodying the features 20 of my invention is shown in the accompanying drawings in which Figure 1 is a view in side elevation of the ironing board folded up against the wall, Fig. 2 is a similar view in front elevation, Fig. 3 is a view in elevation showing the other side of the board as it appears when removed from the wall, Fig. 25 4 is a view in side elevation of the board down in position for use, Fig. 5 is a similar view in plan, Fig. 6 is a view taken as indicated by the line 6 of Fig. 4, Fig. 7 is a view on an enlarged scale taken as indicated by the line 7 of Fig. 2, Fig. 8 is a view taken as indicated by the line 8 of Fig. 7, and Fig. 9 is a view taken as indicated by the line 9 of Fig. 5.

In the drawings, 20 indicates the wall of 35 a room, which is shown in section. 21 indicates the base board and 22 the quarter round. Permanently secured to the wall, about thirty inches above the floor, is a flat board 23, provided at its ends with thumb 40 catches 24.

There is provided a rectangular flat frame 45 adapted to be placed against the wall and under the board 23. This frame is formed of two vertical legs or supports 26, which are joined at their upper ends on the back or wall side by a flat board 27. The board 27 is of substantially the same thickness as the base board 21, so that when the frame is in place against the wall the vertical legs 50 or supports 26 will be spaced from the wall a distance equal to the thickness of the base board and will lie parallel with the wall. The lower ends of the legs 26 are provided with notches 29 on the rear or wall sides in 55 order to accommodate the base board 21. The legs 26 are joined near their lower ends

on the front side (the side farther from the wall) by a cross bar 30. A bar 31 rests on the upper ends of the legs 26 and joins them. The flat board 27 is of sufficient width so 60 that it extends slightly above the upper edge of the cross bar 31, as shown. To the lower side of the cross bar 31 is fastened a slightly wider strip 33 lying between the supports 26. The strip 33 is provided at 65 its center with a notch 34 and thus adapted to receive a horizontal supporting member 36 to be described more in detail hereinafter. When the board is folded up out of use, this horizontal supporting member 36 assumes 70 a vertical position parallel with the wall and moves into the notch 34; the strip 33 projecting forwardly in front of the bar 31 a distance substantially equal to the thickness of such horizontal supporting member 75 36. The strip 33, at one side of the notch 34, is provided with a thumb catch 35 adapted to be turned to hold said horizontal supporting member 36 in the notch 34 and thus hold the ironing board in its folded position 80 up against the wall when not in use.

Attached to the upper side of the cross bar 31 are two parallelly arranged strips 39. Such strips together form what may be termed an ironing board support, that is, 85 a support for the ironing board proper. These strips are attached by means of the hinges 40, so that they may be swung from a horizontal position to a vertical position parallel with the wall 20. Hinged to the 90 free ends of the strips 39 is a rectangular frame comprising the two vertical legs or supports 41, joined at their upper ends on the front side by the cross member 42, near their lower ends by the cross member 43, 95 and at the center by the cross member 44. The hinged connection is formed by means of the hinges 47 which are attached to the inner side of the cross bar 42 and the underside of the members 39, at their ends. 100 The supports 41 are wide enough apart, so that when the board is folded up against the wall the horizontal (when the board is down ready for use) strips 39 will lie between them (see Fig. 2). The horizontal supporting member 36 is hinged at one end to the cross member 30 by means of the hinge 48 and is attached near its outer end by means of the hinge 49 to the cross bar 43. The end 105 50 of the horizontal member 36 is provided with a notch 51 on its upper side, as shown, for a purpose to be explained hereinafter.

Slidably mounted on the members 39 is the ironing board proper, as indicated by 52. The board is held down on the members 39 by means of two cross strips 53 and 54. 5 The strip 53 is fastened to the underside of the ironing board at the center and has its ends thinned, as shown, so that they overlap the strips 39 on the underside. The cross strip 54 is made in substantially the same 10 manner, except that it is held in place by means of a bolt passing through the ironing board on the upper end of which is threaded a wing nut 55. The wing nut 55 serves to draw up the strip 54 and clamp the strips 15 39 between its ends and the bottom of the board, thus enabling the board to be fastened in any desired position. The ends of the strip 53 are just far enough away from the board to permit a relative sliding movement 20 between the board and the strips 39 in shifting the position of the board.

It will be noted that the hinges on the strip 36 are sufficiently far apart so that the legs 41 will slant slightly as shown, when 25 the board is down and ready for use.

The operation of the device is as follows: The board 27 is placed flat against the wall just below the strip 23, so that the legs 26 are close to the wall and parallel therewith. 30 The thumb catches 24 are then turned to hook over the upper edge of the board 27. When the board is down in position ready for use it is as shown in Figs. 4 and 5. It will be noted that sliding adjustment of the 35 board 52 on the members 39 is permitted. When the board is to be folded away out of use, the board proper 52 is slid as far as possible toward the wall (to the left as viewed in Figs. 4 and 5), and the board is 40 then folded up against the wall, as shown in Figs. 1 and 2. In folding the board up this way the wing nut 55 moves into the circular notch 80 provided in the upper edge of the strip 23, and the member 36 moves 45 into the notch 34 where it is held in place by turning of the catch 35. The notch 51 is for the purpose of accommodating the cross

piece 54. The end 50 of the member 36, when the board is folded up, moves to a position just under the lower part of the cross 50 piece 44 and is there held by means of a spring catch 82.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim 60 all novelty inherent in my invention as broadly as possible in view of the prior art.

What I claim as new and desire to secure by Letters Patent, is:

In a device of the character described, a 65 frame, means for detachably securing said frame flat against a wall, an ironing-board support hingedly attached to the upper edge of said frame, whereby the same may be swung from a horizontal position to a vertical position parallel with and close to the wall, said frame comprising two parallelly arranged strips, means for supporting said ironing-board support in its horizontal position, said means comprising a substantially 70 vertically arranged leg hingedly attached to the free end of the ironing-board support, a supporting member hingedly connected at one end to the lower part of the frame and hingedly connected at the other end to the 75 lower end of said leg, means to hold said supporting member in vertical position and an ironing-board slidably mounted on said ironing-board support and provided on its underside with two cross strips having their 80 ends lying under the strips forming the ironing-board support, one of the said cross strips having means to draw it up against the ironing-board support to hold the ironing-board in position.

In witness whereof I hereunto set my hand and seal this 12 day of October, 1921.

MARCUS C. STEARNS. [L.S.]
